Filed July 3, 1961, Ser. No. 121,464

3 Claims. (Cl. 166—4)

This invention relates to methods for recovering oil from an oil-bearing formation in the earth after it has become economically unfeasible to produce the oil by ordinary primary production techniques. More particularly, but not by way of limitation, the present invention relates to a method and apparatus for determining the location and rate of advance of a displacement front formed ahead of a displacement fluid injected into an oil-bearing formation for the purpose of displacing the oil from the point of injection toward one or more producing wells.

The sharp increase in the costs of geophysical exploration and in the production of naturally occurring deposits of liquid fuel in recent years has given rise to a keen reappraisal of secondary recovery techniques. Such procedures as repressuring the formation with an injected gas, flooding the formation with water and other liquids, and, more recently, the process of promoting and sustaining combustion along a moving front in the formation have been used effectively to economically recover residual oil in formations which cannot be produced by direct or primary production methods. In all of the methods of secondary recovery depending upon the introduction of some type of displacement fluid to the formation for the purpose of displacing the oil contained therein toward a producing well, there is a well recognized need for production personnel to be constantly acquainted with the position of the displacement front in the oil-bearing formation, and its rate of advance in the formation. If the position and rate of movement of the displacement front can be accurately known at all times, then other factors in the procedure of secondary recovery can be more closely controlled to improve the efficiency of the production. Thus, the rate and pressure at which the displacement fluid is injected into the formation, as well as the direction of injection, are, in large part, determined by the manner in which the displacement front moves through the formation from the injection well toward the producing wells. It is also important to know the area encompassed by the moving front as it moves outwardly in all directions from the injection well.

Several procedures have been utilized in the past for determining with varying degrees of accuracy the position and rate of propagation of the displacement front in a secondary oil recovery system. One of the earliest and most elementary of the procedures utilized is that of conducting laboratory experiments to determine the approximate speed at which the injected fluid will move through the formation under certain pressures, and then estimating the position of the front in the oil-bearing formation on the basis of the time which has elapsed since commencing the injection, and the pressure and volume of injection which have been utilized.

A method which has been more recently proposed consists in transmitting an electromagnetic wave pulse from the injection well into the oil-bearing formation in the direction of the displacement front. The pulses so transmitted are reflected from the displacement front, which occurs in the form of a vertically extending interface between the displacement fluid and the oil which is being

2

driven before it towards the production wells. The reflected signals are then received by a suitable electromagnetic wave receiver which is also located in the injection well. The travel time of the electromagnetic wave is, of course, indicative of the distance from the injection well to the displacement front. The electromagnetic wave reflection technique has been applied to secondary recovery systems employing in-situ combustion in which a combustion front is moved through the formation from an injection well towards a producing well, and also to secondary recovery methods utilizing superheated steam as the displacement fluid.

Although the electromagnetic pulse technique works well enough in in-situ combustion and superheated steam recovery processes, it does not operate well under a frequently occurring condition in which the earth strata contains a large quantity of water. The method is also beset by difficulties arising from the substantial absorption of such pulses by the earth tending to greatly weaken their intensity prior to their arrival at the ultimate point of reception. Finally, in such reflection techniques, the difference in the characteristics of the formation on opposite sides of the vertical interface formed by the moving displacement front is frequently not sufficiently pronounced to provide a strong reflected signal of sufficient amplitude to permit it to be easily distinguished from noise picked up by the receiver.

The present invention comprises a novel method and apparatus for ascertaining the location and rate of advance of a displacement front produced by continuously injecting a displacement fluid into an oil-bearing formation during a secondary recovery operation. The method is dependent upon the production of a sonic wave, and the observation of the time required for the wave to travel through the oil-bearing formation, contacting, as it does so, the vertical interface between the displacement fluid and the oil at the displacement front. In a preferred embodiment of the invention, the sonic wave is originated at either a production well or the injection well and is transmitted through the formation to a listening station disposed in one of the wells located on the opposite side of the moving displacement front. The sonic wave is thus transmitted through the displacement front, and in the course of such transmission undergoes a change in its velocity as it passes from the portion of the formation which is saturated with the displacement fluid into the oil-bearing portion of the formation.

In a modified embodiment of the invention, the sonic wave is originated at one of the wells and is transmitted in the direction of the displacement front. The wave, upon contacting the vertically extending interface at the displacement front, is reflected back to the well of its origin and is there received by suitable sound receiving apparatus. The time required for the sonic wave to traverse the distance between the well from which it is transmitted and the displacement front, and to then return to the transmitting well, is, of course, a measure of the distance of the displacement front from the transmitting well.

From the methods of the present invention as thus far described, it will now be appreciated that the rate of movement of the displacement front may be determined by transmitting a series of sonic pulses separated by intervals of silence of known duration, determining the distance between the well from which the pulses are transmitted and the displacement front at the time of each transmission, and determining from this data the distance which the displacement front has moved during the time interval between pulse transmissions.

Since, under some conditions of operation, it may be desirable to utilize both the sonic reflection and straight-

through transmission techniques, the invention also resides in the provision of an apparatus by which both the reflection and straight-through methods may be concurrently utilized in the same secondary recovery operation. The apparatus utilized in performing such combined reflection and straight-through methods broadly comprises a sound transmitting device and sound receiving device suspended in at least one of the wells utilized in the secondary recovery project, and also a sound transmitting and sound receiving device located in a second well of the project, which second well is horizontally spaced from the well containing said first mentioned sound transmitting and receiving means, and with said wells being disposed on opposite sides of the moving displacement front.

It is a major object of the present invention to provide a method and apparatus for determining the position and rate of advance of a displacement front of the type occurring in secondary recovery of petroleum utilizing an injected displacement fluid.

Another object of the present invention is to provide a method of determining the position of a displacement front extending 360° around an injection well so that the configuration of the front and the area included within the front may be accurately known.

A further object of the present invention is to provide a system for determining the position and rate of advance of a displacement front in the secondary recovery of oil from an oil-bearing formation, which system may be incorporated in, and utilized with, existing secondary recovery well systems.

An additional object of the present invention is to provide an apparatus for sonically determining the position of a displacement front in an oil-bearing formation, which apparatus is simple and relatively inexpensive in construction, easy to operate, and characterized by a long and trouble-free operating life.

These objects and advantages of the present invention will be better understood, and other useful and advantageous features of the invention will become manifest, upon reading the following disclosure in conjunction with a perusal of the accompanying drawings which illustrate my invention.

In the drawings:

FIGURE 1 is a schematic drawing illustrating a secondary oil recovery system in which the present invention is incorporated.

FIGURE 2 is a plot constructed from data obtained using the method of the present invention. The plot illustrates the advance of the displacement front from the injection well toward the production wells with the passage of time.

FIGURE 3 schematically illustrates a plurality of recorder chart traces as they appear when the method of transmitting sound waves between wells located on opposite sides of the displacement front is utilized.

FIGURE 4 schematically illustrates a plurality of recorder chart traces as they appear when the reflected sound wave method of front location is employed.

FIGURE 5 is a schematic illustration of a secondary recovery system in which a multiple trace recording instrument is utilized to simultaneously record the travel times of sound waves traveling from an injection well to a plurality of surrounding production wells.

FIGURE 6 illustrates a multiple trace recorder chart upon which a plurality of traces have been recorded in correspondence to the travel times of sound waves transmitted from the injection well through a displacement front of the configuration shown in FIG. 5 to several production wells located as shown in FIG. 5.

Referring now to the drawings in detail, and particularly to FIG. 1, reference character 10 designates an injection well extending from the surface 14 of the earth into an oil-bearing formation designated generally by reference character 16. At the surface 14 of the ground adjacent the injection well 10, a supply of a suitable displace-

ment fluid is contained in a reservoir 17. The displacement fluid is pumped from the reservoir 17 by pump 18 into the bore of the injection well and is injected into the oil-bearing formation 16 from the injection well. As the displacement fluid moves radially outward in the oil-bearing formation 16 from the injection well 10, it forces the oil in the formation ahead of it and a displacement front 20 is created in the form of a generally vertical interface between the portion 22 of the formation 16 containing the displacement fluid and that portion 24 of the formation containing the oil being displaced.

One or more production wells 26 extending from the surface 14 into the oil-bearing formation 16 and horizontally spaced some distance from the injection well 10 are provided in accordance with secondary recovery procedures well understood in the art. It will further be understood that, though but a single production well 26 is illustrated in FIG. 1, the common practice in secondary recovery procedures is to provide a plurality of production wells in horizontally spaced relation from a centrally located injection well so that as the oil is displaced radially through 360° from the injection well, it may be simultaneously produced at a number of producing well locations. As has been previously explained, in order to control the efficiency of the production from such wells, it is highly desirable that operating personnel be apprised of the position and progress of the displacement front 20 through the oil-bearing formation 16. The present invention permits the position and rate of advance of the displacement front 20 to be constantly known, thereby vastly improving the efficiency with which such secondary recovery operations may be conducted.

Referring again to FIG. 1, a suitable sound transmitting device 28 and sound receiving device 30 are suspended in the injection well 10 by means of a suitable cable 32. One or more of the production wells 26 may also contain such sound transmitting and receiving devices. The sound transmitting and receiving devices 28 and 30, respectively, are positioned in the bores of the wells in horizontal alignment with the oil-producing formation 16 and are of the type in which an electrical signal is converted to a sonic signal and vice versa. In the preferred embodiment illustrated in FIG. 1, a suitable recording instrument 34 is electrically connected to the transmitter 28 and receiver 30 disposed in the injection well 10, and to the receiver 30 located in production well 26. Thus, the travel time of sonic waves 36 transmitted by the transmitter 28 in the injection well 10 and reflected by the displacement front 20 to receiver 30 in the injection well may be constantly recorded, as may the travel time of sonic waves 38 which are transmitted from the injection well transmitter 28 through the interface of the displacement front 20 to the receiver 30 located in the production well 26.

A second recording instrument 40 is electrically connected to the transmitter 28 and receiver 30 located in the production well 26. The recording instrument 40 may thus be utilized to record the travel time of sonic waves 42 transmitted from the transmitter 28 in the production well 26 to the displacement front 20 and reflected back to the receiver 30 of the production well. From the arrangement of the apparatus depicted in FIG. 1, it will be apparent that following transmission of a sound from either of the transmitters 28 located in either the injection well 10 or the production well 26, a sound wave is reflected from the casing of the respective well and travels, for all practical purposes, directly to the receiver located in the same well as that from which the sound is transmitted. The time required for these "direct" sound waves, designated by reference character 44 in FIG. 1, to travel between transmitter and receiver is very small compared to the travel time of the sound waves 36, 38 and 42 which are transmitted to and through the displacement front 20. As will be appreciated by those skilled in the art, a single multiple trace recorder might

be suitably connected to each of the transmitters 28 and receivers 30 to record the travel times of the several sonic waves transmitted and received in the manner described above.

The manner in which the recorded times of sonic signals may be utilized in practicing the present invention is best illustrated in FIGS. 2 through 5. FIG. 3 depicts a plurality of recorder chart traces, A through E, each of which indicates the time interval elapsing between the instant of transmission of a sonic signal 38 from the injection well 10 and the instant of its reception at the producing well 26—hence, the time required for the sonic wave to travel through the oil-bearing formation 16 between the two wells. The direct path of travel 44 between the transmitter 28 and receiver 30 located in the injection well 10 is relatively short compared to the distance between the injection and producing wells, so that the pip 50, designating the initial pulse pip, produced on the chart 52 by the reception of the directly transmitted signal by the receiver 30 in the injection well 10 may be taken as a reference point corresponding to the time in which the signal is transmitted. When the sound wave 38 is received by the receiver 30 in the production well 26, an electrical signal activates the recording instrument 34 to produce a second pip 54 on the chart. The second pip 54 will be spaced from the initial pulse pip 50 by a distance which is directly proportional to the time required for the sound wave to travel through the oil-bearing formation 16 between the injection well 10 and the producing well 26.

Referring now to FIG. 3, the chart trace at the top of the figure represents the indicia which are recorded on the chart 52 of the recording instrument 34 when a sound wave is transmitted between the injection well 10 and the producing well 26 prior to injection of a displacement fluid into the formation 16. The space separating the initial pulse pip 50 from the received signal pip 54 corresponds to the travel time of a sound wave 38 through the untreated formation. After the displacement medium is injected into the formation, the travel time of a sound wave 38 between the injection and displacement wells will decrease if the velocity of sound is greater in the fluid which is injected than it is in the oil-bearing portion 24 of the formation 16 ahead of the displacement front. Conversely, if the velocity of the sound wave in the injected fluid is less than its velocity in the oil saturated portion 24 of the formation 16, the travel time of the sound between injection well 10 and the production well 26 will be increased.

FIG. 3 illustrates the pattern of the chart traces when water is used as an injection fluid. As the displacement front moves outwardly from the injection well 10 toward the surrounding production wells, the travel times of sound waves 38 progressively decrease by virtue of their greater velocity in the flooded portion 22 of the formation 16 than in the unflooded portion 24 ahead of the front 20. Thus, on the trace marked A, the distance separating pips 50 and 54 on the chart 52 is less than the distance which separates these pips on the uppermost trace which represents the travel time of the sound wave 38 prior to the injection of the water. Trace A is recorded a known time interval, which may also be designated A, after the water is injected. After time interval B has elapsed following the recordation of trace A, another sonic wave 38 is transmitted from the transmitter 28 in the injection well 10 and is received at the receiver 30 in the production well 26. The travel time of this sound wave is recorded on trace B of FIG. 3, and is less than the travel time recorded on trace A, since, in the time interval B, the injection fluid has advanced further toward the production well 26. The procedure of transmitting, receiving and recording the travel times of sound waves transmitted intermittently after known time intervals is repeated to yield traces C, D and E of FIG. 3. The advance of the displacement front with the passage of time

is reflected in the decreasing travel times of the sonic waves as indicated by traces A through E.

After the travel time of the sound wave 38 through the formation 16 at any given time after injection is determined from the recorder chart 52, the distance of the displacement front 20 from the injection well 10 at that time may then be determined if the velocity of the sound in both the treated and untreated portions 22 and 24, respectively, of the formation is known. The latter parameters may be determined in any suitable manner, such as from tables or from measurement at the location of the secondary recovery operation. For example, the uppermost trace in FIG. 3 may be used to obtain the travel time between injection well 10 and production well 26 before the displacement fluid is injected into the formation 16, and since the distance between these wells is known, the velocity of the sound in the untreated portion 24 of the formation 16 may be calculated. The velocity of sound in the displacement fluid may also be measured. With total travel time between transmitting and receiving wells known, as well as the velocity of the sound in the formation on opposite sides of the displacement front 20, the distance of the displacement front from the injection well may be calculated by use of the equation:

$$D = \frac{\frac{T}{V_o} S}{\frac{1}{V_w} - \frac{1}{V_o}}$$

Where,

D is the distance from the injection well to the displacement front;

T is the total travel time of the sound wave from the injection well to the production well;

S is the distance from the injection well to the production well;

V_o is the velocity of sound in the oil saturated portion of the formation ahead of the displacement front; and

V_w is the velocity of sound in the portion of the formation lying between the injection well and the displacement front, that is, the flooded portion of the formation in FIG. 1.

The distance, D, between the injection well and the displacement front as determined by the above equation, is, of course, the distance measured along a line extending between the injection well 10 and one of the production wells 26. Similar calculations can be made for the distance to the front as measured along lines extending between the injection well and the other production wells 56, 58 and 60, so that a plot of the displacement front may be made similar to that shown in FIG. 2. In such a plot, the locations of the front 20 at given times will be indicated by the concentric lines designated by letters A through E, with the distances between each line and the injection well 10 corresponding to the distances between the pips 50 and 54 on the several traces A through E portrayed in FIG. 3. It will be apparent that instead of transmitting the sound wave from the injection well 10 to the production wells 26, 56, 58 and 60, waves could be transmitted from the production wells to the injection well. It will also be understood that the rate of advance of the displacement front 20 may be determined by calculating the distance it has moved in the time between the transmissions of succeeding sound waves.

FIG. 4 illustrates several chart traces of the type recorded when the sound wave reflection method is utilized to determine the position of the displacement front. Thus, at a time A after the displacement fluid has been injected into the oil-bearing formation, a sonic wave 36 is transmitted from the injection well 10 through the formation 16 toward the moving displacement front 20. As explained above, the sound wave is almost immediately directly received by the receiver 30 in the injection well 10 and its reception is indicated by the initial pulse pip

50 on chart trace A. The wave 36 then travels outwardly to the displacement front 20 and a reflected sound wave is returned to the receiver 30 in the injection well 10 as a result of the different densities of the fluid on opposite sides of the vertically extending interface formed at the displacement front 20. When the reflected sound wave is received by the receiver 30 in the injection well 10, a pip 62 is inscribed on chart trace A. As in the change in velocity method of front location depicted in FIG. 3, the travel time of the sound wave in the reflection method is proportional to the distance on the chart which separates the initial pulse pip 50 from the pip 62 representing the reception of the sound wave. However, as FIG. 4 clearly shows, the advance of the displacement front toward the production well 26 is indicated by an increase in the time required for the sound wave to travel from the injection well 10 to the front 20 and be reflected back to the injection well. Thus, since traces A through E in FIG. 4 represent the transmission and reception of sound waves transmitted intermittently and after successively longer periods of time following the initial injection of the displacement fluid, the distance separating the initial pulse pip 50 from the pip 62 inscribed on the chart upon reception of the reflected signal is increasingly large as traces A through E are recorded.

When the reflection method is utilized to determine the location of the displacement front, the distance from the injection well 10 to the front 20 may be calculated using the travel time of the sound wave and the velocity of the sound in the treated portion 22 of the formation 16 in the equation:

$$2D = T_r \cdot V_w$$

Where,

T_r is the total travel time of the sound wave from the injection well to the displacement front and back to the injection well; and

V_w and D have the same definitions as set forth above in the foregoing equation utilized in the change in velocity method.

From the data thus derived from the reflection method of displacement front location, a plot of the front movement identical to that shown in FIG. 2 may be obtained. Of course, an advantage resides in the reflection method which is not shared by the change in velocity method in that the location of more points along the displacement front may be obtained, thus making the plot of the displacement front curve between its intersections with the lines extending between injection and production wells more accurate. On the other hand, under some circumstances which may be occasionally encountered in secondary recovery operations, the reflected sound wave may be very weak so that better results may be obtained using the change in velocity method. It is thus desirable to provide the apparatus depicted in FIG. 1 so that either or both methods may be practiced. It will be apparent, of course, that although the reflection method has been described as it is applied to a sonic wave transmitted from the injection well 10, the wave may also be transmitted and received at the production wells. In the latter event, however, the advantage attributable to the reflection method and described above is lost.

FIG. 5 is a schematic illustration of a multiple trace recorder system utilized in carrying out the method of the present invention so that simultaneous chart readings may be obtained corresponding to the travel times of sound waves between the injection well 10 and a plurality of production wells 1, 2, 3 and 4. Of course, a plurality of recorders may be utilized instead of a multiple trace type, it being only necessary to provide recording equipment capable of simultaneously recording a separate trace for each of the production wells. The change in velocity method of displacement front location is utilized with such a recorder arrangement, and

when a multiple trace recorder is utilized, the chart and data recorded thereon appear as shown in FIG. 6. By referring to FIG. 6, it may be seen that the displacement front has progressed farthest toward production well 2 and least toward production well 3, as indicated by the total travel time distances between the two pips 50 and 62 on each trace. The front has progressed approximately the same distance toward production wells 1 and 4. With this information at hand in the form of specific distances from the injection well 10 to the front 20 as measured along lines extending between the injection well and the several production wells, the form of the front and its relationship to the injection and production wells at any given time may be plotted, and also its rate of advance toward any of the production wells may be calculated.

It will be apparent to petroleum engineers and others concerned with petroleum production by secondary recovery techniques that this ability to constantly follow the movements of the displacement front will be an invaluable aid in properly controlling such factors as the rate and direction of injection of the displacement fluid so that production efficiency can be improved. The method herein disclosed for locating the displacement front, while being described as it may be applied to secondary recovery using water as the displacement fluid, may be utilized in production techniques employing steam, in-situ combustion, or any other system depending upon the displacement of the oil toward the production wells by means of a fluid which is injected into the formation.

Although the method and apparatus of the invention have been described with a certain degree of particularity, certain elements of the apparatus and steps of the method 35 may be altered in ways apparent to those who possess ordinary skill in petroleum production procedures. Insofar as such alternatives involve only the use of elements and steps which are the practical equivalent of those disclosed herein, they are considered to fall within the spirit and scope of the invention as defined by the following claims.

We claim:

1. In a secondary recovery system for recovering oil from an oil-bearing formation of the type characterized by an injection well and at least one producing well, the method of determining the location of a displacement front which comprises:

- (a) injecting a displacement fluid into said oil-bearing formation from said injection well to displace the oil in said formation ahead of a moving interface formed between said fluid and the oil;
- (b) transmitting a sound wave through said formation to said interface from a point in said formation horizontally spaced from said interface on one side thereof;
- (c) detecting said sound wave at a listening station horizontally spaced from said interface and on the opposite side thereof; and
- (d) registering the travel time of said sound wave through the formation from its point of transmission to said listening station whereby the position of said interface in said formation may be determined.

2. A method of effecting the secondary recovery of oil from an oil-bearing formation which comprises the steps of:

- (a) drilling an injection well and at least one production well from the surface to said formation with said production wells horizontally spaced from said injection well and from each other;
- (b) supporting a sound transmitting device in one of said wells at the level of said formation;
- (c) supporting a sound receiving device in one of said wells at the level of said formation;

- (d) injecting a displacement fluid into said oil-bearing formation from said injection well to displace the oil in said formation ahead of a moving interface between said fluid and the oil;
- (e) transmitting a sound wave from said sound transmitting device through said formation through said interface;
- (f) detecting said sound wave at said receiving device located in one of said wells on the opposite side of said interface from the transmitting device 10 so that the registered travel time of said sound wave is the time required for said wave to travel from said transmitting device through said interface to said receiving device; and
- (g) registering the travel time of said sound wave 15 through the formation from said sound transmitting device to said receiving device whereby the position of said interface in said formation may be determined.

3. The method defined in claim 2 characterized further to include the step of registering the times required for a sound wave to travel known distances in said formation on each side of said interface whereby the velocity of sound in said formation on both sides of said interface may be determined.
